UNITED STATES PATENT OFFICE

WEBSTER HENRY LULAND, OF NEWARK, NEW JERSEY, ASSIGNOR TO DEFIANCE MANUFACTURING CORPORATION, A CORPORATION OF NEW YORK

CHECK WRITER

Application filed February 26, 1930. Serial No. 431,540.

This invention relates to improvements in machines used for printing numerical amounts and particularly to machines of the kind known as "check-writing" or "check-printing" machines, by which the amounts are filled in on bank checks, vouchers, etc.

The object of the invention is to provide that, by the simple manipulation of a single control lever, the capacity of a machine of the hand wheel type may be substantially increased; said control lever being so placed that the operator may operate the same, in the course of setting a value in the type drums, without removing his hands from the set-up wheels.

The invention consists in the novel construction and combination of parts as set forth in the appended claims.

In the accompanying drawings:

Fig. 1 is a partly sectional plan view of a machine embodying the invention, with the cylindrical members shown in full.

Fig. 2 is a left-hand elevation showing the control lever and operating gear segment.

Fig. 3 is a detail view of an adjustable stop member for aligning in the extreme positions the control lever, with its corresponding type drums.

Fig. 4 is a detail view of the type wheel locating means.

The illustrated machine is adapted to fill in the amount of a check, voucher, or other form, not only by figures, but also by words. Accordingly, it is normally provided with four type carriers, 1, 2, 3, and 4 in the form of drums or wheels, the wheel 1 bearing type expressive of the whole numbers, up to ninety-nine, in words; the wheel 2 having corresponding numbers in figures; the wheel 3 bearing the word "Dollars" and various fractions of a dollar from 00/100 to 99/100, in figures, and the wheel 4 having the corresponding amounts in figures expressed decimally. Thus, for example, the machine is

arranged to print a check in the following form:

Ninety-one and 31/100 Dollars \$91.31.

It is, accordingly, necessary that the wheels 1 and 2 be rotated always in unison in setting the machine for any required amount, while the wheels 3 and 4 must also be rotated in unison but independently of the wheels 1 and 2. The movements of the wheels 1 and 2 are controlled by a manually rotatable member 5, fixed on the left-hand end of the shaft 6, the position of the wheels being indicated by a graduated index wheel 7, which turns with the main shaft 6 and which is viewed through a member 8 fixed to the casing and formed with a sight-opening. The wheels 1 and 2 and the gear 9 are keyed directly to the shaft 6 so as to turn therewith, gear 9 having teeth engaging with a ratchet member 50 (Fig. 4) thereby locating the type wheels 1 and 2 in exact printing position.

The wheels 3 and 4 are loosely mounted on the shaft 6 and are adapted to be rotated in unison by the manually rotatable member 10, mounted on the extended hub 20 of gear member 11, said gear member being loosely mounted on shaft 6 and having engagement with a pinion 12 fixed on a counter shaft 13 journaled in the casing of the machine by eccentric bearings 14 and 15. This counter shaft carries the pinions 16 and 17, the pinion 16 meshing with the annular series of gear teeth 18 on the type wheel 4 while the pinion 17 meshes with the series of teeth 19 provided on the type wheel 3. A ratchet, similar to that having engagement with the teeth of gear 9, is also provided to engage the teeth 18 on the type wheel 4 to locate the type wheels 3 and 4 accurately. The position of the wheels is indicated by the graduated index wheel 21 fast upon the extended hub 22 of the type wheel 4 and viewed through the sight opening of member 8 fixed to the casing.

To the four type wheels above described

have been added the type wheels 23 and 24, the type wheel 23 printing in the position shown in Fig. 1 a row of stars and bearing also type for printing the words "One hundred", "Two hundred", etc., to "Nine hundred", each value being preceded by a star, as indicated. The type wheel 24 bears a "\$" type in corresponding position to the stars on type wheel 23, and a "\$1", "\$2", etc., in corresponding position to the values on type wheel 23.

Type wheels 23 and 24 are loosely mounted on the shaft 6, and are adapted to be rotated in unison by means of the control lever 35, 15 in the following manner.

For all values less than one hundred dollars, the stars on type wheel 23 and the \$ on type wheel 24 are in printing position; for all amounts between ninety-nine dollars and 20 one thousand dollars, the operator, in setting the values on the type wheels 1, 2, 3, and 4, by means of the set-up wheels 5 and 10, rotates the lever 35, without removing his hands from the set-up wheels, by means of 25 the thumb piece 36, to the desired amount as indicated by the index strip 37 on lever 35 as read through the sight opening in member 8.

One end of lever 35 terminates in a gear 30 segment 38 (Fig. 2) and meshes with a gear member 39 fast to a shaft 28 journaled in the casing of the machine at 29 and 30. Supported on the shaft 28 are the pinions 31 and 32, the pinion 31 meshing with the 35 annular series of teeth 49 on the type wheel 23, and the pinion 32 meshing with the similar series of teeth 41 provided on the type wheel 24.

Rotation of the operating lever 35 will, 40 therefore, through its gear segment 38 and the gear 39, rotate the shaft 28, and the pinions 31 and 32 will rotate the respective type drums 23 and 24 to the desired position. A ratchet, similar to the ratchet having engagement with gear 9, is also provided to 45 engage the teeth 49 on the type wheel 23 to locate the type wheels 23 and 24 accurately.

A pin 42, in gear 39, is provided to limit the movement of lever 35 by contacting with 50 the surfaces 43 and 44 (Fig. 3) of a collar or sleeve 45 adjustably mounted upon the bearing 29 by means of the set screws 46.

I claim:

1. In a check-writer or the like, having a 55 plurality of type carriers and means including an automatically located hand wheel adapted to be grasped in the hollow of the hand and operable to set one of said type carriers selectively to bring different type 60 to printing position; selective setting devices for another of said type carriers, including a thumb lever located adjacent said hand wheel, and within reach of the thumb of the hand upon said wheel.

65 2. In a check-writer or the like, having two

series of type carriers and means including an automatically located hand wheel adapted to be grasped in the hollow of the hand and operable to set a type carrier of each series selectively to bring different type to printing position; selective setting devices for other of said type carriers, including a thumb lever located adjacent said hand wheel and within reach of the thumb of the hand upon said wheel, and operating connections between 70 said lever and a type carrier of each series.

Signed at Orange in the county of Essex and State of New Jersey this 21 day of Feb. A. D. 1930.

WEBSTER HENRY LULAND.
